UNITED STATES PATENT OFFICE.

FURMAN D. SPEAR, OF NEW YORK, N. Y., ASSIGNOR TO ARMSPEAR MANUFACTURING COMPANY, OF NEW YORK, N. Y.

SIGNAL-LAMP.

1,103,546.

Specification of Letters Patent. Patented July 14, 1914.

Application filed July 15, 1913. Serial No. 779,124.

To all whom it may concern:

Be it known that I, FURMAN D. SPEAR, a citizen of the United States, residing at New York, in the county of New York and 5 State of New York, have invented a new and useful Improvement in Signal-Lamps, of which the following is a specification.

This invention relates to signal lamps which are used mainly in railroad service, for instance, as classification lamps on locomotives, as marker lamps at the rear end of trains, on semaphores and on switch stands. The conditions under which signal lamps are used for these and other purposes and 15 the requirements which such lamps should fulfil vary greatly. For instance, for some uses it is desirable that the lamp should have a lens which has a field or horizontal spread of considerable width, while for 20 other uses a lens is desirable which concentrates the light in a beam and has a corresponding long range. For still other uses it is desirable that the lamp should have both styles of lenses, one which has a wide, 25 fan-like field or spread and one which concentrates the light in a beam, as for instance on a switch stand where a beam of light is required for a straight main track and a wide, fan-like illuminated zone which 30 covers one or more curved tracks joining the main track.

The object of this invention is to produce a signal lamp in which the flame chamber is composed of removable and interchangeable transparent lens sections and opaque sections or panels, arranged circumferentially side by side, the transparent lens sections being constructed to spread the light and one or more of the opaque panels or 35 sections being provided with a lens which concentrates the light in a beam.

In the accompanying drawings: Figure 1 is a sectional elevation of a signal lamp provided with these improvements. Fig. 2 is a horizontal section on line 2—2, Fig. 1, showing the lamp provided with two lens sections and two opaque sections, one of the opaque sections being provided with a circular lens. Fig. 3 is a perspective view of one of the lens sections. Fig. 4 is a perspective view of the opaque section provided with a circular lens. Fig. 5 is a horizontal section similar to Fig. 2, showing a lamp provided with one transparent section 50 and three opaque sections.

The frame of the lamp may be of any suitable construction, for instance it may be constructed as shown in the drawings or as shown in the application of Furman D. Spear, filed September 18, 1912, Serial No. 721,077, or in the application of Judson S. Pixley, filed September 18, 1912, Serial No. 721,059.

As shown in the drawings, the lamp frame comprises a base 10, upright bars 11 which are secured at their lower ends to the base, a breast 12 which is detachably secured to the upper ends of the bars by screws 13 entering flanges 14 on the bars, and a top 15 hinged to the breast.

The flame chamber, as shown in Fig. 2, is composed of four sections, two transparent lens sections 16, 16, and two opaque sections 17, 18, all of the same size and configuration so that these sections are interchangeable. The four sections together form a spheroidal flame chamber having its axis arranged vertically and having flat ends. Each section has its side edges arranged in radial planes and each lens section is constructed above and below its equatorial zone with horizontal refracting rings which project the rays of light in a fan-like or spreading field or area. The opaque section 17 is provided with a circular lens 19 which is secured in a goggle or collar 20 surrounding an opening in the section. This lens is arranged in the proper relation to the flame and of proper construction to concentrate the light in a beam which issues from the lamp at right angles to the vertical axis thereof.

The transparent lens sections 16 are provided with horizontal refracting ribs arranged preferably on the inner side of the sections or are otherwise so constructed as to spread the light horizontally in a fan-like or diverging zone. When each lens section extends over one-fourth of the circumference of the flame chamber, the field or spread of the light emitted by one lens section is practically equal to 90 degrees. These lens sections and opaque sections form together a circular flame chamber which is preferably of spheroidal form, as shown, the same having horizontal upper and lower circular ends and increasing in diameter from each end toward the middle.

The individual lens sections may be of the same color or of different colors and their number may be greater or less according to

circumstances, for instance there may be one, two or three lens sections and a corresponding number of opaque sections if the flame chamber is composed of four sections. The total 5 number of sections may, however, be greater or less than four. The adjacent side faces of the sections are so constructed as to form joints which are practically water and air proof in order to prevent disturbance of the 10 flame under the severe conditions under which signal lamps are used. For this purpose the adjoining flat sides of the sections are preferably each provided with a groove 21 which extends from end to end of the section and 15 in which a packing strip 22 of asbestos or other suitable material is arranged.

The base of the lamp is provided with a circular seat for the sections of the flame chamber and this seat is preferably provided 20 with a rubber gasket 23 on which the sections rest. The upper ends of the sections may be tied together by a rubber gasket 24. The breast 12 bears upon the gasket 24 and holds the sections firmly in position.

25 25 represents the oil pot and 26 the burner, which parts may be of any suitable construction and supported on the base of the lamp in any suitable manner.

As the lens sections and opaque section 30 are alike in size and configuration they are interchangeable and a flame chamber of the desired character can be readily formed by selecting and combining the particular kinds of sections which are necessary for the purpose, thus enabling the same kind of lamp 35 frame to be utilized for lamps having various combinations of sections.

I claim as my invention:

1. A signal lamp comprising a lens having 40 the form of a spheroidal section with its sides arranged in radial planes, the section being constructed above and below its equatorial zone with refracting rings arranged

circumferentially and adapted to project the rays of light in a fan-like area. 45

2. In a signal lamp, the combination with a lamp frame, of a spheroidal flame chamber removably secured therein and composed of interchangeable transparent and opaque spheroidal sections arranged circumferentially 50 side by side and having their continuous sides arranged in radial planes, each transparent section being constructed above and below its equatorial zone with refracting rings arranged circumferentially and adapted 55 to project the rays of light in a fan-like area.

3. The combination with a lamp frame, of a flame chamber having a removable opaque section which is clamped between the base 60 and breast of the frame and provided with a lens.

4. The combination with a lamp frame, of a flame chamber composed of interchangeable sections arranged circumferentially side 65 by side, one of which sections is opaque and provided with a circular lens.

5. The combination with a lamp frame, of a flame chamber comprising interchangeable transparent and opaque sections arranged 70 circumferentially side by side, one of which opaque sections is provided with a circular lens.

6. The combination with a lamp frame having a base and a movable top portion, of 75 a removable sectional flame chamber arranged between said base and top portion and comprising an opaque section having a circular lens.

Witness my hand, this 7th day of July, 80 1913.

FURMAN D. SPEAR.
